UNITED STATES PATENT OFFICE.

EWALD GEORGE BAUM, OF NATICK, MASSACHUSETTS.

ETHER-CONE.

1,317,122.

Specification of Letters Patent. Patented Sept. 23, 1919.

Application filed May 20, 1919. Serial No. 298,528.

To all whom it may concern:

Be it known that I, EWALD G. BAUM, a citizen of the United States, and a resident of Natick, county of Middlesex, and State 5 of Massachusetts, have invented a new and Improved Ether-Cone, of which the following is a full, clear, and exact description.

This invention relates to medical appliances. More in particular it relates to means 10 for giving anesthetic applications to patients, and relates directly to what is known in the medical science as an ether cone.

An object of the invention is to provide an apparatus to be used in administering anesthetics to patients for the purpose of putting them to sleep for surgical operations or other medical attention.

Another object of the invention is to provide a surgical device or ether cone to be 20 used in particular for administering ether. It is a primary purpose of the invention to design an ether cone which may be quickly assembled and disassembled and which will comprise a set of metal fittings used in connection with certain ether administering 25 means so that the portions of the appliance which come in contact with the patient may be thrown away or destroyed after use, while the permanent metal fittings will be sterilized and retained for continual use.

With the above and other objects in view the invention has relation to a certain combination and arrangement of parts, an example of which is described in the following 35 specification, pointed out in the appended claims, and illustrated in the accompanying drawings, wherein:

Figure 1 shows a plan view of the ether cone.

Fig. 2 shows a vertical sectional view taken upon the line 2—2 of Fig. 1.

Fig. 3 shows a sectional view taken upon the line 3—3 of Fig. 2.

Fig. 4 shows a sectional view taken upon the line 4—4 of Fig. 2.

Fig. 5 illustrates a view taken upon the 45—5 of Fig. 2.

Referring now more in particular to the drawings, the numeral 6 points out a conically-shaped paper form with open top and open bottom with a section 5 cut from one side of the larger end. The paper form will be manufactured of any appropriate light weight pasteboard or other material, and 50 will be shaped into a partially flat form as shown in the sectional view 3 when as-

sembled. In use the paper form is placed upon the patient's face inclosing the nose and mouth, and the opening 5 is provided to fit over and around the patient's nose. 60

A cloth cover 7 sewed up in a shape substantially the same as the paper form is adapted to be slipped over the paper form with the lower ends of the cloth cover turned upwardly on the inside of the paper 65 form as designated by the numeral 8. The upper end of the cloth cover will terminate flush with the open end of the paper form.

The cloth cover and paper form are placed one over the other with the lower extremity 70 of the cover punched or placed upwardly into the form and placed over the patient's face. The patient inhales and exhales into the paper form and cloth cover assembly. After use the paper part is discarded or 75 burned up to insure thoroughly antiseptic conditions, and the cloth cover is washed, boiled or otherwise sterilized for further use.

A metal absorbent container 9 shaped conically to conform to the paper form 80 and with open ends, is inserted in the upper portion of the paper form. This absorbent container is filled with loosely packed absorbent cotton or other suitable material which will hold ether or other anesthetics. 85 The upper portion of the absorbent container is reduced slightly in diameter.

A valve tube 10 is inserted through the open end of the assembly with a grooved valve seat 11 engaging the reduced neck or 90 opening of the absorbent container 9. The valve tube 10 and the absorbent container may be soldered together so as to form a unitary structure. The valve seat 11 is formed in the tube by spinning a groove 95 into the light metal tube, or by otherwise forming it therein.

An inhaling valve comprising a ball 14 is carried in the lower portion of the valve tube 10 and confined therein by inwardly 100 turned ears 15 which are punched in from the wall of the tube. The ears confine the inhaling valve in the lower portion of the valve tube and adjacent the valve seat 11. The lower portion of the valve tube is 105 swaged out along the wall thereof from the lower end of the tube upwardly to the valve seat. This provides air openings 16 between the ball and the valve tube. Thus when the ball is in normally downward position air can be inhaled through the appliance by passing downwardly past the 110

ball through the swaged-out portions 16. The valve tube forms a guide for the ball to move upwardly and downwardly to engage the valve seat or be supported upon 5 the ears.

An ether funnel 18 made of metal, rubber, or other material, is provided with a funnel neck 19. The lower portion of the funnel neck 19 is flared out conical-shaped 10 and provided as a fabric retaining cap 20. The neck of the funnel is fitted over the valve tube and the fabric retaining cap 20 pushed down upon the fabric holding it in tight and immovable position thereupon.

When the several parts of the device are 15 assembled the whole structure forms a substantial and composite device. The fabric retaining cap is compressively engaged with the cloth which imparts a pressure to the 20 cloth and paper form thus tightly clamping the cloth and paper form between the retaining cap 20 and the absorbent container 9.

In use the device will be fitted over the 25 patient's mouth and nose and ether administered through the funnel 18. The absorbent material helps to carburet and volatilize the ether, and as the patient inhales he draws a charge of air heavily laden with 30 ether into his mouth or nose. As the patient exhales the inhaling valve closes against the seat 11 thus preventing ether from passing out of the device. The exhaled air from the patient will find its way outwardly 35 along the bottom edges of the paper form. The lower edges and surplus portions 8 of the cloth cover are pushed upwardly into the open cone or paper form to catch and absorb any excess of ether which may trickle 40 downwardly from the absorbent container.

The device can be quickly taken apart, and the paper and absorbent elements thereof destroyed or burned, while the cloth cover and metal fittings comprising the absorbent 45 container, valve, tube, and ether funnel will be sterilized and preserved for further use.

This form of medical appliance will fill 50 a long-felt want for a dependable and sanitary anesthetic administrator. The device is extremely light in weight, simple to use and inexpensive to manufacture.

The paper cone and cloth cover may be put together and used as an ordinary closed

cone in an emergency without inserting the metal parts. This may be done where the 55 metal parts are not accessible for use.

Having thus described my invention, what I claim as new, and desire to secure by Letters Patent is:

1. An anesthetic administrator, comprising in combination; a conically shaped paper form, a conically shaped cloth cover placed over the paper form, means for holding absorbent material in the paper form, a valve tube inserted within the paper form, an inhaling valve contained within the valve tube, a funnel attached to the valve tube, and a fabric retaining cap carried by the funnel. 60

2. An anesthetic administering device, comprising in combination; a paper form to be placed over the patient's face, an absorbent container fitted on the inside of the paper form, cloth placed within the paper form to catch an excess of liquid anesthetic, a valve tube fitted into the absorbent 75 container, a funnel placed over the valve tube, and a flared-out cap integrally formed with the funnel and fitted over the paper form. 70

3. An anesthetic administrator, comprising in combination; a paper form, a cloth cover placed over the paper form, an absorbent container fitted into the paper form and removable therefrom, an inhaling valve associated with the absorbent container, a 80 liquid receiving funnel fitted in the inhaling valve, and a fabric retaining cap integrally formed with the funnel to clamp the cloth to the paper form. 85

4. An anesthetic administrator, comprising in combination; a conically shaped paper form, a means for holding absorbent material in the paper form, a valve tube inserted within the paper form and associated with the means, an inhaling valve contained within the valve tube, and a funnel attached to the valve tube. 90

5. An anesthetic administrator, comprising in combination, a conically shaped paper form, a conically shaped cloth cover placed over the paper form, a device for holding absorbent material in the paper form, a valve tube inserted within the paper form and connected with the device, and an inhaling valve within the valve tube. 100

EWALD GEORGE BAUM.
